UNITED STATES PATENT OFFICE.

WILLIAM P. AYLSWORTH, OF COUNCIL BLUFFS, IOWA.

HOUSE-MOVING TRUCK.

SPECIFICATION forming part of Letters Patent No. 290,513, dated December 18, 1883.

Application filed August 16, 1883. (No model.)

To all whom it may concern:

Be it known that I, WILLIAM P. AYLSWORTH, a citizen of the United States, residing at Council Bluffs, in the county of Pottawattamie and State of Iowa, have invented certain new and useful Improvements in House-Moving Trucks, of which the following is a specification, reference being had therein to the accompanying drawings.

10 This invention relates to certain improvements in hauling-trucks; and it has for its objects improved means whereby the fore wheels and axle can be turned to the right or left and held in any of those positions. These objects 15 I attain by means illustrated in the accompanying drawings, in which—

Figure 1 represents a perspective view of my improved truck, and Fig. 2 represents a top view of the tongue thereof.

20 In the drawings, the letter A indicates the wheels of the truck, mounted upon suitable axles, B. Bolted to the upper side of the hind axle are three reach-bars, C, which extend forward and rest on the fore axle. The forward ends of these reach-bars C are held securely together by a metallic strap or band, D, by means of bolts, thereby forming a clevis, to which is hitched the pulling force or teams when necessary. Passing through the center 25 reach-bar, and just in front of the fore axle, and down through a staple secured to the axle, and then through an ear which is formed on one end of a metallic brace which extends back and is secured at its other end to the center reach-bar, behind the fore axle, is the king-bolt E, thus permitting the fore wheels and axle to turn either to the right or left. The 30 top of the axle and the under side of the reach-bars nearest the king-bolt are provided with 35 metallic plates to prevent wear. About midway between the axles, and on top of the reach-bars, there is secured a cross-piece, F, to which is fastened a metallic plate, on which the bolster G turns, the bolster being held by means 40 of a bolt, H, which passes through to the under side of the reach-bars. To the fore axle 45

are secured thills, to which is secured a tongue, I, having at its forward end plates J, on the upper and lower sides, they having apertures for the reception of a bolt. Working in connection thereto is a segment, K, also provided with apertures for the reception of a bolt, and extending forward and being a part thereof is an arm having apertures, the purpose of which will be more fully hereinafter described.

50 55 The operation of my invention is as follows:

In moving houses generally it requires four trucks—one at each corner of the building. Then the bolster is placed longitudinally; but where only two trucks are used the bolsters 60 are placed transversely. In all cases, whether two or more trucks are used, the tongues of the hind trucks are provided with plates, as shown in the drawings, the front trucks having ordinary wagon-tongues. The segment 65 with apertures and a forwardly-extending arm is fastened, by means of bolts or otherwise, to the under side of the building to be moved, so that the apertures in the plates on the tongue will come in conjunction with the apertures in 70 the segment. Thus the bolt can be placed in any of the apertures, holding the fore axle in any desired position.

Having thus described my invention, what I claim, and desire to secure by Letters Patent, 75 is—

A hauling-truck constructed substantially as shown and described, having a tongue fastened thereto, provided with plates at its forward end, on its upper and lower sides, these 80 plates having apertures, in combination with a segment having apertures, and also being provided with a forwardly-extending arm adapted to be secured to the under side of the building or object being moved, as and for the 85 purposes herein set forth.

In testimony whereof I affix my signature in presence of two witnesses:

WILLIAM P. AYLSWORTH.

Witnesses:

DAVID TOSTEVIN,
R. T. BRYANT.
